Application September 26, 1938, Serial No. 231,724

17 Claims. (Cl. 166—21)

This invention relates to well drilling and producing and relates more particularly to a method and apparatus for repairing well liners, well casings, and the like. A general object of the invention is to provide an efficient method and a simple, practical and very effective apparatus for repairing or closing openings in well liners, well casings, etc.

The liners installed in the producing portions of wells sometimes develop holes that admit sand and other solid matter to the well in excessive quantities to interfere with the production. These holes have various origins, for example, they may be caused by a corrosive or abrasive action or by the operation of certain tools or equipment in the well. Similar holes are found in well casings and quite frequently are the points of entrance of unwanted fluid to the wells.

Another object of the invention is to provide a method for repairing a leak in a well liner or casing that assures the complete sealing off of the leak.

Another object of the invention is to provide a method for repairing well casing, well liners, etc., that permits the well casing or liner to be cleared for drilling operations, or the like.

Another object of this invention is to provide a repair liner that may be readily installed in a well to repair or close off an opening in a well liner, or the well casing.

Another object of this invention is to provide repairing equipment of the character mentioned that may be easily and quickly set in the operative condition in the well without disturbing the liner or the well casing.

Another object of this invention is to provide a device or repair liner of the character mentioned that does not interfere with the production of the well or with the operation of the well pump or the other well equipment.

Another object of this invention is to provide a repair liner of the character mentioned that is drillable to be quickly and easily removed from the well by drilling it up with drilling tools. The repair tool or device of the invention may be easily disposed of or removed, when such a course becomes desirable or necessary, by merely operating a suitable drilling tool in the well to drill the device up and reduce it to small cuttings or fragments and flushing the cuttings from the well.

Another object of this invention is to provide a drillable repair section or liner of the character mentioned that forms dependable fluid-tight seals with the interior of the liner or casing at points above and below the opening or hole in the

liner or casing to insure a secure, positive shut off.

The various objects and features of our invention will be fully understood from the following detailed description of typical preferred manners of carrying out the method and typical forms and applications of the apparatus, throughout which description reference is made to the accompanying drawings, in which:

Fig. 1 is a side elevation of one form of the invention arranged in position in a well liner showing the parts in the normal or unactuated positions with the liner in vertical cross section. Fig. 2 is an enlarged longitudinal detailed sectional view of the upper portion of the tool with the packer actuated showing the body and a portion of the setting string in elevation. Fig. 3 is an enlarged longitudinal detailed sectional view of the lower portion of the tool with the packer set, showing the lower tail-piece and the body in elevation. Fig. 4 is a side elevation of another form of the invention in a well liner with the lower packer actuated. Fig. 5 is an enlarged longitudinal detailed sectional view of the upper portion of the tool shown in Fig. 4 illustrating the manner in which the upper packer is actuated, and Fig. 6 is a view similar to Fig. 5 showing the upper packer actuated.

The equipment or apparatus of the present invention may be embodied in forms for repairing the different tubular structures and members employed in deep wells, such as oil wells and gas wells. In the following detailed description we will describe two typical preferred forms of apparatus of the invention employed in accordance with the method of the invention to repair typical well liners. It is to be understood that the invention is not to be construed as limited or restricted to the particular forms or applications about to be described, but is to be taken as including any features or modifications that may fall within the scope of the claims.

The repair device or apparatus of the invention illustrated in Figs. 1, 2 and 3 comprises, generally, a drillable tubular body 10, drillable packing means A and B carried by the upper and lower portions of the body 10 to seal with the interior of a well liner L, and means 11 for lowering and setting the tool.

The body 10 of the repair tool or device is an elongate tubular member or structure adapted to be introduced into the liner L. The body 10 is proportioned to readily pass through the liner L and may be of substantial length to extend beyond the upper and lower ends of the hole H in

the liner L when the tool is in position in the well. The construction of the body 10 may be varied considerably. For example, the body may be formed of one or more lengths of pipe or tubing of the required diameter. In the particular case illustrated in the drawings the body 10 is made up of three lengths or sections 12, 13 and 14 of tubular stock or pipe. The body sections 12, 13 and 14 may be connected by suitable couplings 15. The body 10 is preferably provided at its lower end with a guide 16 to facilitate the passage of the tool into the liner L. In accordance with the invention the body 10 is drillable, that is, it is formed of a material that may be drilled up or reduced to cuttings or fragments by a suitable drilling tool operated in the well. In practice the body 10 may be formed of aluminum, aluminum alloy, cement, glass, suitable plastic materials, etc., or combinations of such materials.

20 The packing means A and B are provided on the upper and lower portions, respectively, of the body 10 to seal with the interior of the liner L above and below the hole H. The packing means A and B are such that they may be operated by manipulation of the body 10 when the tool is in the well. The vertically spaced packing means A and B may be similar or identical in construction and we have designated corresponding parts of the means A and B with corresponding reference numerals. Where the body 10 comprises the three sections 12, 13 and 14 the packing means A is carried on the upper section 12 while the packing means B is supported on the lower body section 14.

30 Each packing means A and B includes one or more rings 17 of packing material surrounding or encircling the body 10. In the case illustrated each packing means A and B includes two packing rings 17 separated by a spacer 18. The ends 40 of the spacers 18 are outwardly convergent and the ends of the rings 17 are shaped to conform to the ends of the spacers. The uppermost packing ring 17 of each means A and B engages against a fixed abutment on the body 10. In the typical construction illustrated in the drawings the uppermost ring 17 of the means A bears against the lower end of an adapter or reducing nipple 19 threaded on the upper end of the section 12. The engaging ends of the nipple 19 and the said packing ring 17 slope upwardly and outwardly. The uppermost packing ring 17 of the means B may engage against the lower end of an adapter 20 interposed between the body sections 13 and 14. The adapter 20 may be threaded on the upper end of the section 14 and may be connected with the section 13 by a coupling 15. The engaging ends of the adapter 20 and the uppermost packing ring 17 of the means B preferably slope upwardly and outwardly. The rings 17 are constructed of a suitable deformable and compressible packing material capable of withstanding the fluids in the well. In practice the rings 17 may be formed of lead. The spacers 18, the nipple 19 and the adapter 20 are all constructed 55 of a drillable material or of drillable materials such as aluminum, aluminum alloy, Bakelite, or the like.

Each packing means A and B further includes a slip and tail-piece control. Each of these controls comprises a cone sleeve 21 shiftable on the body 10. The upper ends of the sleeves 21 engage upwardly against the lowermost packing rings 17 of the means A and B and the engaging ends of the sleeves and packing rings preferably 70 slope downwardly and outwardly. The sleeves 21

have conical or downwardly and inwardly tapering external surfaces. Sets of slips 22 are engaged on the sleeves 21 to be actuated thereby. The outer sides of the slips 22 are toothed to effectively grip the interior of the liner L for the purpose of resisting or preventing downward movement of the sleeves 21. Reins 23 are connected with the slips 22 and extend downwardly therefrom. The lower ends of the reins 23 are secured to shiftable rings 24 surrounding the body 10. Shiftable rings 25 encircle the body 10 below the rings 24 and outwardly bowed leaf springs 26 extend between and connect the adjacent spaced rings 24 and 25. The springs 26 are adapted to frictionally engage the interior of the liner L to 15 resist movement of the associated slips 22. Latch means are provided for initially or normally holding the slips 22 in their down and retracted positions. These latch means may comprise pairs of diametrically opposite hook-like latches 27 depending from the rings 24. The latches 27 are adapted to engage pins 28 on the body 10 to releasably latch the slips 22 in their down and retracted positions. The latches 27 may be such that they are released from the pins 28 by a partial rotation of the body 10 in a left-hand direction, followed by a downward movement of the body.

The sleeves 21, the slips 22, the reins 23, the rings 24 and 25, and the latches 27 are constructed 30 of drillable material or materials, to be readily drilled up when the tool is in the well. The slips 22 may be constructed of cast iron so that their teeth may effectively bite into the interior of the liner L. When formed of cast iron the slips 22 are 35 quite brittle and are readily reduced to fragments or cuttings by a drilling tool operated in the well. When the latches 27 are engaged with the pins 28 the slips 22 are retracted to readily enter the liner L with clearance and the packing rings 17 40 are substantially flush with the spacers 18, the reducer 19 and the adapter 20 to have clearance with the interior of the liner.

The means 11 is provided to lower the tool into the selected position in the liner L and to set or 45 actuate the tool so that its packing means A and B seal with the liner above and below the hole H. The means 11 includes a tubular member or adapter 30 on the upper end of the body 10 and a mandrel 31 secured to the lower end of a setting 50 string 32. In the typical construction illustrated the adapter 30 is threaded on the reduced upper portion of the reducer 19. In accordance with the invention the adapter 30 is drillable being formed of aluminum, aluminum alloy, a suitable plastic 55 material, or the like. The adapter 30 is preferably of substantially the same inside diameter as the reducer 19 and the body 10. Two diametrically opposite internal grooves are provided in the adapter 30. Each of these grooves has a vertical entrance 33 extending downwardly from the upper end of the adapter 30 and terminating at its lower end in a horizontal branch 34. Vertical groove arms 35 extend up and down from the lower ends of the horizontal branches 34. 60

The mandrel 31 is an elongate member adapted to be received in the adapter 30. The mandrel 31 is fixed to the lower end of the setting string 32 which may be in the nature of a string of drill pipe, tubing, or the like. Two diametrically opposite lugs 36 are provided on the mandrel 31 to cooperate with the grooves in the adapter 30. The lugs 36 are adapted to be passed through the groove entrances 33 and the branches 34 into the groove arms 35. When the lugs 36 are in the ver- 70

tical groove arms 35 they serve to connect the tool with the string 32 so that the tool may be run into the well on the string and may be turned by means of the string.

5 In the method of the invention when employing the tool illustrated in Figs. 1, 2 and 3 of the drawings the position of the hole H to be repaired or closed is first determined. The tool is secured to the lower end of the string 32 by the 10 means 11 described above, and the tool is run into the well on the string. The tool is lowered to a position in the liner L where its packing means A and B are substantially equally spaced above and below the hole H. The string 32 is then 15 turned and lowered to release the pins 28 from the latches 27. The lugs 36 cooperating with the groove arms 35 transmit these movements from the string 32 to the tool. The springs 26 frictionally engaging the interior of the liner L resist or 20 prevent movement of the rings 24 during the release of the pins 28 from the latches 27. Following the release of the pins 28 from the latches 27 the string 32 is moved downwardly to set the slips 22 and actuate the two packing means A and B. 25 During the downward movement of the body 10 with the string 32 the springs 26 resist or prevent downward movement of the slips 22 so that the cone sleeves 21 move down within the slip assemblies to force the slips outwardly into tight gripping engagement with the interior of the liner L. 30 Thus the slips 22 serve to prevent downward movement of the sleeves 21 and as the downward movement of the body continues the packing rings 17 are compressed and distorted into sealing engagement with the interior of the liner L. It will be apparent how the sleeves 21 form fixed 35 abutments against which the packing rings 17 are compressed by the reducer 19 and the enlargement 20 fixed on the downwardly moving body 10. It is to be observed that the two packing means A and B are simultaneously released or conditioned for operation and then simultaneously set or actuated. The lugs 36 engage in the bottoms of the lower groove arms 35 to transmit the above 40 described downward movement from the string 32 to the body 10.

Following the actuation of the packing means A and B the string 32 is raised slightly and then turned to move the lugs 36 through the horizontal branches 34 of the grooves in the adapter 30. The string 32 is then raised to move the lugs 36 up out of the entrances 33 of the grooves. This disconnects the mandrel 31 and the string 32 from the tool and the string 32 may then be withdrawn from the well. The packing means A and B serve to dependably and effectively seal between the interior of the liner L and the exterior of the tubular body 10 to prevent fluid or solid matter entering the hole H from reaching the 50 interior of the liner L. It will be observed that there is a large clear passage extending through the repair device from one end to the other that provides for a free flow of fluid and allows tools and equipment to be run into and out of the liner without interference. The packing means A and B are such that they remain set and effective indefinitely and the device does not require repair or replacement.

When it becomes desirable or necessary to operate drilling tools in the well for the purpose of deepening the well or for other purposes the repair device may be easily and quickly removed from the liner by drilling it up. A suitable drilling tool may be operated in the liner to drill up 55 the repair device or reduce it to small fragments

or cuttings that are readily washed or circulated from the well by the circulation fluid employed in the rotary method of well drilling. As described above, the several parts of the repair device are constructed of drillable material and the tool may be easily drilled up when in the well. This is highly important as liners, and the equipment connected therewith, installed in wells for substantial periods quite frequently become so tightly sanded and embedded in the well that it is difficult, if not impossible, to remove them. With the repair device of the present invention it is unnecessary to attempt to withdraw the device after it has been in the well for a substantial period as it may be easily and quickly removed by drilling it up.

The form of the invention illustrated in Figs. 4, 5 and 6 of the drawings may be said to comprise, generally, a body 10^a, spaced packing means A' and B' on the body 10^a, and means 11^a 20 for setting and actuating the repair liner or tool.

The body 10^a may be similar in construction to the body 10 described above. As illustrated in the drawings, the body 10^a comprises an upper section 13^a and a lower section 14^a connected by a 25 coupling 15^a. The body sections 13^a and 14^a are elongated tubular members and are proportioned to be received in the liner L with suitable clearance. The body 10^a is of sufficient length to extend some distance above and below the hole H in 30 the liner L when the repair section is in position in the liner. In accordance with the invention the body 10^a is drillable, that is, it is constructed of a drillable material such as aluminum, aluminum alloy, cement, a suitable plastic material, or 35 the like, to be drilled up or reduced to fragments by a drilling tool when in the well.

The lower packing means B' is arranged on the lower section 14^a of the body 10^a and is operable to seal with the interior of the liner L below the 40 hole H therein. As illustrated in the drawings, the packing means B' may be identical with the packing means A and B described above, and the reference numerals applied to the elements of the packing means B have been used to designate corresponding parts of the packing means B'.

The upper packing means A' is arranged at the upper end of the body 10^a and is operable to seal with the interior of the liner L above the hole H. The means 11^a includes an extension or 50 tubular member 40 attached to the upper end of the body 10^a. In the particular construction illustrated in the drawings the member 40 is secured to the upper end of the body section 13^a by means of a threaded coupling 41. The member 55 40 and the coupling 41 are formed of a drillable material, for example, they may be constructed of the same material as the body sections 13^a and 14^a. The member 40 forms the adapter of the setting and actuating means 11^a, as 60 will be more fully described.

The packing means A' further includes packing rings 42 on the member 40. The rings 42 encircle or surround the member 40 and are spaced apart by a suitable spacer 43. A shiftable follower 44 is arranged on the member 40 to engage down against the upper end of the uppermost ring 42. A pin and slot connection 50 connects the follower 44 with the member 40 for vertical movement thereon. The packing 70 rings 42 are constructed of a deformable packing material such as lead and the spacer 43 and the follower 44 are constructed of drillable material such as aluminum, aluminum alloy, or the like. The lowermost packing ring 42 has its lower end 75

engaged against the upper end of the coupling 41. The ends of the packing rings 42 are preferably outwardly divergent and the ends of the spacer 43, the follower 44 and the coupling 41 engaging the rings are pitched to conform with the shape of the rings. The packing rings 42 are initially of substantially the same diameter as the collar 41 to readily enter the liner L and the rings are distortable under compression to engage and seal 10 against the interior of the liner L, as shown in Fig. 6.

The means 11^a for setting and actuating the device includes or provides a pair of diametrically opposite grooves in the tubular member 40, described above. Each of these grooves includes a vertical entrance 45 extending downwardly from the upper end of the member 40 and a horizontal branch 46 at the lower end of the entrance. Vertical groove arms 47 extend up and down from 20 the branches 46 in spaced parallel relation to the entrances 45. The means 11^a further includes a mandrel 48 fixed or secured to the lower end of a setting string 32^a of drill pipe, tubing, or the like. The mandrel 48 is of substantial length 25 and is provided at its lower end with an enlargement 51. The enlarged 51 carries diametrically opposite lugs 52 cooperable with the grooves in the interior of the member 40. The lugs 52 are adapted to be passed through the entrances 45 30 and the branches 46 of the grooves into and out of the vertical arms 47. When the lugs 52 are in the groove arms 47 they serve to connect the repair section with the mandrel 48 and the string 32^a.

35 The setting and actuating means 11^a further includes a bell 53 on the mandrel 48 for actuating the packing means A'. The mandrel 48 is provided with a long, rather steep, thread 54 and the bell 53 has an internal thread mating with 40 the thread 54. The lower portion of the bell 53 is enlarged in diameter to pass down over the upper portion of the member 40. The lower end of the bell 53 is flat and adapted to bear against the upper end of the follower 44. Means 45 is provided on the bell 53 to frictionally engage the interior of the liner L to resist movement of the bell. Circumferentially spaced leaf springs 55 have their upper ends attached to the bell 53. The springs 55 are bowed outwardly to frictionally engage the interior of the liner L. The lower portions of the springs 55 may be shiftable in vertical grooves 56 in the exterior of the enlarged lower portion of the bell 53. The bell 53 is initially on the upper portion of the mandrel 48 to be clear of the member 40 and the packing means A' when the tool is run into the well. When the bell 53 is threaded down the mandrel 48 it is adapted to extend beyond the lower end of the enlargement 51 to cooperate with the following 60 lower 44.

In the method of employing the form of the invention illustrated in Figs. 4, 5 and 6 of the drawings the hole H to be closed off is located and the repair liner or device is run into the well 65 on the string 32^a to enter the liner L and assume a position where its packing means A' and B' are spaced above and below the hole H. When the device has been arranged in the proper position the string 32^a is turned to disengage the pins 28 from the latches 27 and is then lowered to actuate the slips 22. During downward movement of the body the cone sleeve 24 of the means B' forces the slips 22 out into tight engagement with the liner L and the slips operate to hold the sleeve 70 against further downward movement. Continued

downward movement of the body 10^a effects the compression and distortion of the packing rings 17 so that they tightly seal with the interior of the liner L at a point below the hole H. It will be observed that the slips 22 set or actuated as just described serve to support the device in the liner L and to hold the device against movement.

Following the actuation of the packing means B' the string 32^a is moved upwardly and given a partial turn to move the lugs 52 into the horizontal branches 46 of the grooves in the member 40. The string 32^a is then moved upwardly to withdraw the lugs 52 from the grooves and to move the mandrel 48 to a position where it is spaced above the tool. The string 32^a is then rotated 10 in a direction to cause the bell 53 to be threaded down the mandrel 48. During this rotation of the string 32^a the springs 55 cooperate with the interior of the liner L to resist turning of the bell. The string 32^a is rotated until the bell 53 is 15 threaded down to the enlargement 51 on the lower end of the mandrel 48. The string 32^a is then lowered to engage the lower end of the bell 53 with the upper end of the follower 44. The string 32^a may then be lowered or moved downwardly so 20 that the bell 53 exerts a downward force on the follower 44. This downward force on the follower 44 compresses the packing rings 42 and distorts them or expands them to seal with the interior of the liner L. When the packing rings 42 have 25 been actuated or expanded the string 32^a is raised and withdrawn from the well. The repair device is then fully set or actuated.

The packing means A' and B' carried by the imperforate tubular body 10^a and sealing with 30 the interior of the liner L at points above and below the hole H prevent the passage of fluid and solid matter from the hole H into the liner. The repair device serves to fully and dependably close off the hole H in the liner L. The packing 35 means A' and B' are such that they remain effective indefinitely. The device has through its full length an unobstructed opening which closely approximates the diameter of the liner L and which permits passage through the device of 40 pumping and other well equipment and tools of sizes required to properly continue operations in the well. In the event that it becomes desirable or necessary to deepen the well or to carry on other operations below the repair device, the device 45 may be easily removed from the well by merely drilling it up. A suitable drilling tool may be operated in the well to reduce the repair section of the invention to small cuttings or fragments that are washed from the well by the circulation fluid. The several parts of the repair device are constructed of drillable material and are easily and quickly drilled up by a drilling tool.

While we have described the method and apparatus of the present invention as utilized to seal off holes in well liners, it is to be understood that they may be employed in a similar manner to repair or to seal off holes in well casings and 50 other tubular objects installed in wells.

Having described only typical preferred manners of carrying out the method of our invention and typical forms and applications of the apparatus, we do not wish to be limited or restricted 55 to the specific details herein set forth, but wish to reserve to ourselves any variations or modifications that may appear to those skilled in the art or fall within the scope of the following claims.

Having described our invention, we claim:

1. The method of repairing a leak in a tubular object in a well comprising inserting in said object a drillable tubular body having vertically spaced packing means operable to pack with the interior of said object above and below said leak, and subsequently drilling up said body and packing means.
2. A device for repairing a tubular object in a well comprising a tubular body to be inserted in said object, vertically spaced packing means on the body operable to pack with the interior of said object, and means for releasably connecting the body to a setting string by which the body may be lowered into said object and the packing means actuated, said body and packing means being constructed of drillable material whereby the device may be drilled up in the well.
3. Apparatus for sealing off an opening in a tubular object in a well comprising a tubular body to be introduced into the object, packing means on the body operable to seal with the interior of the object at points above and below the opening, and a member mounted upon the upper end of the body adapted to be releasably connected to a setting string by which the body may be lowered into the object and the packing means actuated.
4. Apparatus for sealing off an opening in a tubular object in a well comprising a tubular body to be introduced into the object, packing means on the body operable to seal with the interior of the object at points above and below the opening, and a member mounted upon the upper end of the body adapted to be releasably connected to a setting string by which the body may be lowered into the object and the packing means actuated, the body, packing means and said member being formed of drillable material whereby they may be drilled up in the well.
5. Apparatus for sealing off an opening in a tubular object in a well comprising a tubular body to be introduced into the object, packing means on the body operable to seal with the interior of the object at points above and below the opening, each packing means including slips for gripping the interior of the object and deformable packing, and a member mounted upon the body adapted to be releasably connected to a setting string by which the body may be installed in the object and the packing means actuated, the body, packing means and member being formed of drillable material whereby they may be drilled up in the well.
6. Apparatus for sealing off an opening in a tubular object in a well comprising a tubular body to be introduced into the object, packing means on the body operable to seal with the interior of the object at points above and below the opening, each packing means including packing deformable under compression and an abutment on the body for the packing, and means at the upper end of the body for releasably connecting with a setting string, the body and each of said means being formed of drillable material whereby the assembly of the same may be removed from the well by drilling it into fragments by a drilling tool.
7. Apparatus for sealing off an opening in a tubular object in a well comprising a tubular body to be introduced into the object, packing means on the body operable to seal with the interior of the object at points above and below the opening, each packing means including an abutment on the body, deformable packing com-
- pressible by the abutment to seal with said object, and slips operable to grip the said object and hold the packing against movement whereby movement of the body may deform the packing to seal with the object, and means for moving the body.
8. Apparatus for sealing off an opening in a tubular object in a well comprising a tubular body to be introduced into the object, packing means on the body operable to seal with the interior of the object at points above and below the opening, each packing means including an abutment on the body, a shiftable cone on the body, slips operable by the cone to grip the interior of the object to hold the cone against movement, and deformable packing on the body between the abutment and cone deformed to seal with the object by movement of the body subsequent to actuation of the slips, and means for moving the body to actuate the packing means.
9. Apparatus for sealing off an opening in a tubular object in a well comprising a tubular body to be introduced into the object, packing means on the body operable to seal with the interior of the object at points above and below the opening, each packing means including an abutment on the body, a shiftable cone on the body, slips operable by the cone to grip the interior of the object to hold the cone against movement, and packing on the body between the abutment and cone deformable to seal with the object by movement of the body subsequent to actuation of the slips, and means for moving the body to actuate the packing means; the body and said means being constructed of drillable material so that they may be drilled up after being installed in the well.
10. The method of closing off an opening in a tubular object in a well comprising inserting a drillable tubular body in the object, the body having packing, actuating the packing to seal with the object, and subsequently drilling up the body and packing to leave the said object clear.
11. Apparatus for sealing off an opening in a tubular object in a well comprising a tubular body to be inserted in the object, packing means on the body operable to seal with the interior of the object below the opening, packing means on the body operable by compression to seal with the interior of the object above the opening, means for releasably connecting the body to a setting string, and a threaded member mounted on the setting string adapted to be threaded to a position to compress the last named packing means.
12. Apparatus for sealing off an opening in a tubular object in a well comprising a tubular body to be inserted in the object, packing means on the body operable to seal with the interior of the object below the opening, packing means on the body operable by compression to seal with the interior of the object above the opening, a releasable means for connecting the body to a setting string, a threaded member adapted to be mounted on the setting string, and means on the member for frictionally engaging the object whereby rotation of the setting string following its release from the body threads the member to a position to compress the packing upon downward movement of the setting string; the body and the packing means being formed of drillable material whereby they may be drilled up by a drilling tool operated in the well.
13. Apparatus for sealing off an opening in a tubular object in a well comprising a tubular body to be inserted in the object, packing means on the body operable to seal with the interior of the

- object below the opening including slip means for gripping the interior of the object, and packing compressible against the slip means by movement of the body, a mandrel attachable to a setting string, a releasable connection between the mandrel and the body whereby the packing means may be actuated by movement of the body, packing means on the body compressible to seal with the interior of the body above said opening, a member threaded on the mandrel, and means on the member engaging the object to resist rotation of the member whereby the setting string may be rotated following its release from the body, to thread the member to position to compress the last named packing means.
14. The method of repairing a tubular object in a well comprising providing a drillable tubular body having spaced drillable packers, inserting the body and packers in said object, actuating the packers to seal with the object, and subsequently drilling up the body and packers to leave the object clear for operations in the well.
15. The method of repairing a leak in a well casing comprising providing a drillable tubular

body having vertically spaced drillable packing means, installing the body in the casing to have the packing means above and below the leak, actuating the packing means to seal with the casing, and subsequently drilling up the body and packing means to leave the casing clear for operations in the well.

5

16. The method of shutting off a hole in a well liner comprising providing a drillable tubular body with vertically spaced drillable packing means, installing the body in the liner to have the packing means above and below the hole, actuating the packing means to seal with the liner, and subsequently drilling up the body and packing means with a drilling tool to leave the liner clear.

10

17. The method of repairing a leak in a tubular object in a well comprising providing a drillable tubular body, installing the body in the object to close off the leak, and subsequently drilling up the body to leave the object clear.
